The ornamental design for an object detection system for electric vehicle charging, as shown and described.

DESCRIPTION

FIG. 1 is a front right perspective view of an object detection system for electric vehicle charging showing our new design;

FIG. 2 is a rear right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side view thereof; and,

FIG. 8 is a right side view thereof.

The broken lines shown in the drawings illustrate portions of the object detection system for electric vehicle charging that form no part of the claimed design.
